UNITED STATES PATENT OFFICE.

MALON INGHRAM FLOWERS, OF WAELDER, TEXAS, ASSIGNOR OF ONE-HALF TO ARCHIE PIERCE SALE, OF WAELDER, TEXAS.

AIR-BRAKE ATTACHMENT.

1,223,267.

Specification of Letters Patent. Patented Apr. 17, 1917.

Application filed February 9, 1917. Serial No. 147,575.

To all whom it may concern:

Be it known that I, MALON I. FLOWERS, a citizen of the United States, and a resident of Waelder, in the county of Gonzales and State of Texas, have invented a new and useful Improvement in Air-Brake Attachments, of which the following is a specification.

My invention is an improvement in air brake attachments, and has for its object to provide mechanism for use in connection with railway cars for automatically controlling the air brakes to cause the same to be applied when a truck is derailed.

In the drawings:

Fig. 1 is a top plan view of the attachment connected to the truck of a railway car with the parts in normal position,

Fig. 2 is a similar view showing the truck derailed,

Fig. 3 is a top plan view of the attachment,

Fig. 4 is a side view,

Fig. 5 is a sectional view showing the valve in normal position, and

Fig. 6 is a similar view showing the valve in open position.

The present embodiment of the invention is shown in connection with the truck 1 of a railway car and the attachment is arranged within the air-line of the air brake system. The attachment comprises a valve casing 3 interposed within the length of the train pipe, the said casing having oppositely arranged internally threaded nipples 4 with which the ends of the train pipe are engaged.

The casing also has a bore 5 extending transverse to the axis of the nipples 4, the said nipples having a common axis, and the said bore is tapered and is adapted to receive a valve 6, shaped to fit the casing and having a transverse port 7 which normally registers with the nipples 4. The valve is also provided with a second transverse port 8 and this port has an exhaust outlet 9 communicating with the atmosphere.

The valve has at the outer end thereof a perforated ear 10, and this ear is connected with the controlling mechanism to be described. The said mechanism comprises a lever 11 which is pivotally mounted on the car by means of a rod 13. This lever is arranged with one end adjacent to the valve 6, and the other end is pivotally connected to the bolster of the truck by means of a

link 14. The lever has a head 15 at the end adjacent to the valve and under normal conditions this head bears against the valve, as shown more particularly in Figs. 3 and 4.

The lever is provided with a cross head 16 near the valve and intermediate the ends of the lever, and the cross head is connected to the ear 10 of the valve by a pair of links 17. These links 17 are pivoted to the ear at one end of the links and to the ends 18 of the cross head at the other. The links are longitudinally slotted as shown at 19, and the rivets 19 which connect the cross head to the links pass through the slots.

It will be evident from the description, 70 that so long as the parts are in normal position on the rails, there will be no movement of the valve, because the slots 18 permit a limited movement of the lever 11 with respect to the valve to compensate for inequalities and curvatures in the track, and the head 15 of the lever will prevent accidental displacement of the valve from jar or jolting. Should, however, the wheels leave the rails, as shown in Fig. 2, the displacement of the truck will swing the lever 11 and will cause the valve to be moved from the position shown in Fig. 5 to that shown in Fig. 6, bringing the exhaust port 8 into register with the train pipe 2 and the brakes 85 will be set, stopping the train at the earliest possible moment.

It will be noticed that the link 14 is connected to the bolster with a lost motion connection, the lever being slotted at the bolster for engagement by the pin which connects it to the bolster. This connection provides for lost motion in transit.

I claim:

1. The combination with a railway car 95 and a train pipe, of a valve casing interposed in the length of the said pipe, said casing having a tapering port transverse to the pipe, a valve in the casing having a port normally registering with the train 100 pipe and having a second port communicating with the atmosphere and adapted to register with the train pipe when the valve is moved longitudinally, and a connection between the said valve and the truck for 105 moving the valve when the truck is displaced with respect to the pipe beyond a predetermined distance, said connection comprising a lever pivoted to the car, said lever having a head engaging the valve 110

when the parts are in normal position to hold the valve closed, the lever having a cross head intermediate its ends, a connection between the end of the lever remote

5 from the valve and the truck, links connecting the valve with the ends of the cross head and having a lost motion connection with the same.

2. The combination with a railway car
10 and a train pipe, of a valve casing inter-
posed in the length of the said pipe, a valve
in the casing having a port normally regis-
tering with the train pipe and having a
15 second port communicating with the at-
mosphere and adapted to register with the
train pipe when the valve is moved longitu-
dinally, and a connection between the said
valve and the truck for moving the valve
when the truck is displaced with respect to
20 the pipe beyond a predetermined distance,
said connection comprising a lever pivoted
to the car, said lever having a head engaging
the valve when the parts are in normal pos-
ition to hold the valve closed, the lever hav-
25 ing a cross head intermediate its ends, a
connection between the end of the lever re-
mote from the valve and the truck, links
connecting the valve with the end of the
cross head and having a lost motion connec-
30 tion with the same.

3. The combination with a railway car and a train pipe, of a valve casing interposed in the length of the said pipe, said casing having a tapering port transverse to the pipe, a valve in the casing having a port normally registering with the train pipe and having a second port communicating with the atmosphere and adapted to register with the train pipe when the valve

is moved longitudinally, and a connection 40 between the said valve and the truck for moving the valve when the truck is displaced with respect to the pipe beyond a predetermined distance.

4. The combination with a railway car 45
and a train pipe, of a valve casing inter-
posed in the length of the said pipe, a valve
in the casing having a port normally regis-
tering with the train pipe and having a
second port communicating with the atmos-
phere and adapted to register with the train
pipe when the valve is moved longitudi-
nally, and a connection between the said
valve and the truck for moving the valve
when the truck is displaced with respect to 50
the pipe beyond a predetermined distance. 55

5. The combination with a railway car and a train pipe, of a valve casing interposed in the length of the said pipe, a valve in the casing having a port normally registering with the train pipe and having a second port communicating with the atmosphere and adapted to register with the train pipe when the valve is moved longitudinally, a connection between the said valve and the truck for moving the valve when the truck is displaced with respect to the pipe beyond a predetermined distance, said connection comprising a pivoted lever connected at one end to the truck and engaging at the other the valve to normally hold the valve closed, and a cross head on the lever having a lost motion connection at its ends with the valve. 60 70
